FRIEZE SCHRÖTER, OF WILMERSDORF, NEAR BERLIN, GERMANY.

IGNITION DEVICE FOR INTERNAL-COMBUSTION ENGINES.

1,128,017.

Specification of Letters Patent.

Patented Dec. 29, 1914.

Application filed July 3, 1913. Serial No. 777,230.

To all whom it may concern:

Be it known that I, FRITZ SCHRÖTER, a subject of the King of Prussia, residing at 4 Duisburgerstrasse, Wilmersdorf, near Berlin, Germany, have invented certain new and useful Improvements in Ignition Devices for Internal-Combustion Engines; and I do hereby declare the following to be a full, clear, and exact description of the invention.

10 The present invention relates to ignition devices for internal combustion engines and particularly to spark plugs, the object of my invention being to provide a plug of improved construction adapted to give longer and better service than those of similar type now generally employed.

In the accompanying drawing, Figure 1 is a vertical section through a plug of the type to which my invention relates and in which my invention is embodied in one form; Fig. 2 is an inverted plan of this plug.

It has already been proposed to make spark plugs for internal combustion engines which have one or both poles of the plug covered with or formed out of non-metallic substances in the group of conductors of the second class which become partially conductive at the high temperature of the explosion cylinder, and in their highly heated condition ionize the adjacent portion of the compressed gas charge traversed by the spark, with the result that the minimum sparking potential between the electrodes is lowered, the formation of the spark facilitated, and the insulation of the spark plug, as well as the high tension apparatus, subjected to materially less demand.

40 Conductors of the second class include various substances which while not good conductors at ordinary temperatures (as are all conductors of the first class), become conductors when heated. Such for instance are 45 oxides of alkali earth metals, thorium oxid, yttria, the glowers used in Nernst lamps, etc. Some ferric oxides (such for example as magnetite) are of the same class. Although these are poor conductors at ordinary temperature, their conductivity is greatly increased when heated. Further, alloys of non-metallic substances which are fair conductors at ordinary temperatures, may be mentioned. Examples of these are silicon 55 and boron, both of which at high temperatures become excellent conductors. The part

g, hereinafter mentioned, may, for example, be composed of 95 per cent. magnetite, 3 per cent. oxid of yttrium or zirconium, 2 per cent. calcic fluorid—the latter for solidifying the material which may be compressed while moist into small cylindrical rods and burned at red heat.

60 The present invention relates to spark plugs of this type and rests upon the discovery that these so-called "active" substances which facilitate the making of the spark, are slowly consumed by the play of the spark thereon even when they are molded under heavy pressure. It has been found that the 65 rapidity of their consumption is proportional to the length of time the arc is maintained; consequently it is desirable to minimize as far as possible the play of the arc upon these substances and this is accomplished according to the present invention, 70 as follows: The central pole piece of the spark plug is formed for example as a small cylindrical rod of so-called "active" substance compressed in a mold, and is so arranged with relation to the opposite pole piece that the spark jumps from the latter to the central rod which in its heated condition augments ionization. It is a matter of 75 common knowledge that an arc struck between two upright conductors at a point of least resistance, tends to rise as the gas between the electrodes becomes heated by the arc, until the arc finally breaks, when the distance between the conductors becomes too 80 great for the predetermined tension of the current to span. This is the principle of the well known horn-shaped lightning arrester. This action of the spark is recognized here, and the upper portion of the central electrode upon which the spark plays, is 85 made of metal, so that while the lower portion is made of "active" material upon which the arc is struck, the upper portion upon which the arc almost immediately plays 90 and is maintained for a longer period, is formed out of a metal which can withstand the action of the arc without material injury. Inasmuch as the play of the arc upon the central rod is shortened to a minimum, 95 its life is not materially less than of the plug as a whole. Furthermore, some kinds of the so-called "active" substances diminish in efficiency in the course of time. This loss of 100 efficiency is confined however to the regions 105 upon which the arc has played continuously for a considerable time. According to the 110

present invention this difficulty is obviated by moving a new portion of the central rod into the arc area, as it is consumed by the play of the arc. This may be automatically accomplished by the pressure of a spring which feeds the rod into the arc area as it is consumed.

Referring to the illustrative embodiment of my invention shown in the accompanying drawing, the metallic body of the spark plug is brought into electrical engagement with the explosion cylinder through the threaded section *c* of the plug which is screwed into the cylinder head. The high tension current is led to the central electrode through the rod *d* insulated by the sleeve *e*. To insure the jump of the spark between the electrodes proper, a skirt *f* of insulation is provided as usual. The rod *d* carries at its lower end a bushing *b* within which is fitted the central pole piece *a* which is pressed outward against the abutment *i* by the spring *h*. As the lower portion of the pole piece is consumed, the upper portion is automatically fed downward by the spring *h*. At the lower end of the body of the plug two downwardly extending arms *l* are provided which carry the three-quarter ring *a* constituting the other pole of the plug. This ring is beveled on its lower face so as to present an edge at its inner periphery at such a height that after the striking of the arc between it and the pole piece *a*, the arc passes at once to the conical portion *k* of the center contact and outward and upward thereon until it breaks. The pole *a* and the conical portion *k* of the center contact may be made out of or covered with suitable metal which will withstand the play of the spark without material injury.

It would of course be no departure from the scope of the present invention, to construct in the manner described not only the central electrode which is connected to the high tension apparatus at the moment of the ignition of the gases, but also the outer pole which is in electrical engagement with the head of the explosion cylinder,—a construction which is readily effected without further explanation than has already been given. While perhaps somewhat difficult to manufacture and expensive, it is easily conceivable. Similarly, the invention would be embodied in a construction in which by the use of a magnetic field in well known manner, the arc may be shifted from the active substance on which it is struck to the metallic portion of the plug, in substantially the same manner as above described. Such a construction appears to be entirely superfluous however, since the com-

bustion gases themselves on explosion have a strong upward driving action on the arc, which is sufficient to effect the desired result.

I claim as my invention:

1. A spark plug having an electrode comprising a conductor of the second class having at high temperature an ionizing action on the adjacent gas traversed by the spark, and a juxtaposed metallic portion upon which the arc plays after its formation.

2. A spark plug having an electrode comprising a conductor of the second class having at high temperature an ionizing action on the adjacent gas traversed by the spark, and a superposed metallic portion upon which the arc plays after its formation.

3. A spark plug having an electrode comprising a conductor of the second class having at high temperature an ionizing action on the adjacent gas traversed by the spark, and a juxtaposed metallic portion to which the arc automatically moves after its formation upon said substance.

4. A spark plug having an electrode comprising a conductor of the second class having at high temperature an ionizing action on the adjacent gas traversed by the spark, and a juxtaposed metallic portion upon which the arc plays after its formation, said conductor of the second class being movably mounted in the plug whereby it may be fed into the arc area as consumed, substantially as described.

5. A spark plug having an electrode comprising a conductor of the second class having at high temperature an ionizing action on the adjacent gas traversed by the spark, and a juxtaposed metallic portion upon which the arc plays after its formation, said conductor of the second class comprising a movable body and means to automatically feed the latter into the arc area as consumed.

6. A spark plug having an electrode comprising a conductor of the second class having at high temperature an ionizing action on the adjacent gas traversed by the spark, and a juxtaposed metallic portion upon which the arc plays after its formation, said conductor of the second class comprising a movable body and spring means to automatically feed the latter into the arc area as consumed.

In testimony whereof I have signed my name to this specification, in the presence of two subscribing witnesses.

FRITZ SCHRÖTER.
